UNITED STATES PATENT OFFICE.

CHAUNCEY REIGART, OF EASTON, PENNSYLVANIA, ASSIGNOR TO TAYLOR-WHARTON IRON AND STEEL COMPANY, OF HIGH BRIDGE, NEW JERSEY, A CORPORATION OF NEW JERSEY.

APPARATUS FOR FORMING HOLLOW ARTICLES.

1,314,366.

Specification of Letters Patent. Patented Aug. 26, 1919.

Application filed December 4, 1918. Serial No. 265,233.

To all whom it may concern:

Be it known that I, CHAUNCEY REIGART, a citizen of the United States, residing at Easton, in the county of Northampton and 5 State of Pennsylvania, have invented certain new and useful Improvements in Apparatus for Forming Hollow Articles, of which the following is a specification.

This invention relates to the art of forming tubular or hollow articles from solid 10 blanks or billets.

In the manufacture of shell forgings, the general practice is to compress a heated billet or metal blank and then to displace the 15 metal by a punching operation. The lower or billet receiving and holding die being fixed or stationary, the displaced or extruded metal generates considerable side friction; hence the die liner is comparatively short-lived. Again, since both the 20 die and the punch are served with a general taper, the ultimate shell body is more or less deformed so that a subsequent drawing operation is necessary to insure concentricity.

25 Objects of the present invention are to provide for rapidly, and, with a minimum number of operations, forming shell bodies of substantially true concentricity; to provide for reducing the side friction before 30 alluded to, and for easing the forging operation as a whole; and more specifically to provide a floating die whereby the aim and purposes of the invention are accomplished.

The nature, characteristic features and 35 scope of the invention will more readily be understood from the following description taken in connection with the accompanying drawing, forming a part hereof, wherein,

Figure 1 is a vertical sectional view of so 40 much of a shell forging apparatus as is necessary to illustrate the application of the invention, the floating die being in its lowest position, the billet compressed therein and undergoing displacement by the 45 piercing or forming punch.

Fig. 2 is a similar view illustrating how 50 the die is elevated coincident with the extrusion or displacement of the metal, thereby relieving the strain on the die, saving wear on the liner by appreciable reduction of skin friction, and in a word making for better forgings.

According to my invention the fixed die-

pot 5 is provided with a relatively movable die 6, the range of movement being determined, if necessary or desirable, by the shoulders 7 and 8 with which the die and die-pot are respectively provided.

55 By this construction and arrangement it will be evident to those skilled in the art that during the shell forging operation the die 6 will float or rise in the pot 5 coincident with the displacement of the metal of the billet 9. Moreover, since it is unnecessary to form the liner 10 on tapering lines, shell 60 bodies of substantially true concentricity are formed, thus dispensing with the usual drawing operation. The invention also promotes rapidity of manufacture because it 65 relieves the strain or pressure on the several 70 parts.

When the punch is withdrawn, the die 6 is free to drop back and does fall back to its initial position. The shock of the fall is cushioned or absorbed by provisions, such 75 as the coiled springs 11 lodged in pockets in the base plate 12. The die is prevented from leaving the die-pot by the shoulders 7 and 8.

The liner 10, the end-forming plate 13, 80 the billet compressing and displacing member 14, knock-out pin 15, and other accessories are or may be as is usual.

Having described the nature and objects 85 of the invention what I claim as new and desire to secure by Letters Patent, is:—

1. In apparatus of the type recited, the combination of billet compressing and displacing means, a fixed die-pot, a billet-holding die susceptible of relative movement in 90 response to a metal-displacing operation, and shock-absorbing provisions for the die.

2. In apparatus of the type recited, the combination of billet compressing and displacing means, a fixed die-pot, a floating 95 die, means for ejecting the formed article, and shock absorbing provisions for the die.

3. In apparatus of the type recited, the combination of billet compressing and displacing means, a fixed die-pot, a floating 100 die, coöperating abutments on said die-pot and die for determining the range of movement of the latter, and a cushion for the die.

4. In apparatus of the type recited, the combination of billet compressing and displacing means, a fixed die-pot, a billet-hold- 105

ing die susceptible of relative movement in response to a metal-displacing operation, means to prevent the accidental displacement of the die, and shock-absorbing provisions for the die.

5. In apparatus of the type recited, the combination of a base plate, a die-pot fixed

thereon, a floating die, a shock absorbing element intermediate the die and base plate, and a knock-out pin movable in the base plate.

In testimony whereof I affix my signature.

CHAUNCEY REIGART.
